IRONING MACHINE CABINET

John A. Castricone, Peoria, Ill., assignor to
 Altorfer Bros. Company, Peoria, Ill., a corpora-
 tion of Illinois

Application March 24, 1939, Serial No. 263,856

10 Claims.

(Cl. 38—56)

This invention relates to ironing machines and more particularly to an improved ironing machine cabinet. Due to the increasingly competitive nature of the market, manufacturers of domestic ironing machines have been called upon to develop cabinets for housing such machines of a design as to lend themselves to economical methods of manufacture and production methods of assembly.

In the prior art it has been customary to mount the ironer roll and shoe on some form of table and to provide a removable cover for the roll, and it has also been common practice to provide table extensions which may be dropped at the sides of the table in order to conserve space when the machine is not in use, or which may be raised to a horizontal operating position to assist in supporting the work when the machine is in operation.

In all of the machines heretofore in use, however, the arrangement of parts has been to a certain degree impractical in that even when the machine cabinet is in its closed or inoperative position, certain parts of the table surfaces, which may from time to time contact the garments being ironed are exposed in such a manner that they may accumulate dirt. Inasmuch as in the ordinary household an ironing machine is used only periodically and is allowed to remain without attention in a laundry room for a long period of time, it will be readily appreciated that the amount of dirt and dust which may settle on any exposed surface will require that all operating surfaces of the machine be completely cleaned by hand before the machine is ready for use.

It is, therefore, a primary object of this invention to provide an ironing machine cabinet wherein all work contacting surfaces are enclosed and protected against the accumulation of dirt or dust when the machine is not in actual operation.

Another object of the invention is to provide an ironing machine cabinet including a work table, a machine cover, and table extension members for the work table, the arrangement being such that the work table extensions may be pivoted upwardly to form end panels for the machine cover.

Another object is to provide an ironing machine table in which table extension panels are mounted on hinges and wherein the hinge mechanisms are recessed below the plane of the work contacting surfaces.

Another object of the invention is to provide an ironing machine cabinet having hinged work table extensions so mounted as to be co-extensive with the surface of the work table when positioned at the extreme lower limit of their movement.

A further object is to provide an ironing ma-

chine cover comprising a three-sided roll enclosure adapted to cooperate with hinged table extensions movable upwardly to close the open ends of the roll enclosure.

5 Another object of the invention is to provide an ironing machine cabinet mounted on casters or other mechanisms whereby it is readily movable along the floor when in closed position, but is anchored or restrained against such movement when in open position.

Another object of the invention is to provide an ironer cabinet including a machine cover and having mechanisms responsive to the manual manipulation of this cover for locking the machine cabinet in fixed position on a floor.

Another object of the invention is to provide an ironing machine and cabinet wherein the movement of the several parts from an inoperative position to an operative position changes the 20 position of the center of gravity of the structure, and wherein means are provided to alter the size or position of the effective supporting base of the cabinet to compensate for such change.

Another object is to provide an ironing machine cabinet which is attractive and symmetrical in appearance and economical in manufacture.

In practicing the principles of this invention, any desirable means may be used for supporting the main ironing machine table which constitutes the principal portion of the work contacting surface. This table is preferably, although not necessarily rectangular in shape, of a length only slightly greater than the overall length of the ironing machine roll mounted thereon, and is mounted on casters at each corner to facilitate free movement from place to place on the floor.

In order to cover the roll and table and thus protect these parts during the idle periods of the 40 machine, a roll enclosure or hood is constructed which includes a top panel and front and rear panels, but which need not be provided with end panels for reasons that will hereinafter appear. It should be pointed out that certain very important manufacturing economies can be accomplished by the use of this three-sided roll enclosure, since it lends itself readily to manufacture by sheet metal stamping without the necessity for any deep drawing or similarly expensive operations.

Table extensions are provided at each end of the ironing table and are mounted on hinges in such a manner that when positioned at their extreme lower limit of movement they will provide 55 working surfaces contiguous with the surface of the main ironing table and when moved upwardly they will assume a vertical position at each end of the three-sided machine enclosure, thus closing the open ends of this enclosure and at the same time forming an attractive and symmetrical

external appearance of the machine. In the present design these table extensions may be of a width equal to that of the table, since they are so designed as to blend symmetrically with the machine design in either open or closed position, and thus require no recesses in which they may be concealed when not in use, as has been customary in the prior art.

Referring now more particularly to the drawings:

Fig. 1 is a front elevation of the preferred embodiment of this invention, the cabinet being shown in its closed or inoperative position;

Fig. 2 is an end elevation of the cabinet in closed position;

Fig. 3 is a perspective view of the cabinet and ironing machine mounted therein, the several parts being shown in the open or operating position of the device;

Fig. 4 is a detail sectional view taken on the plane of the line 4-4 in Fig. 2 and illustrating the hinge means whereby the table extension members are mounted upon the main ironing table;

Fig. 5 is a fragmental rear elevation illustrating one of the roll enclosure hinges;

Fig. 6 is a detail sectional view taken upon the line 6-6 in Fig. 5.

Fig. 7 is a fragmental end elevational view of the machine (partly in section) illustrating the operative connection between the cover hinges and an auxiliary support and brake mechanism;

Fig. 8 is a view similar to Fig. 7, but illustrating the several parts in their operative positions; and

Fig. 9 is a rear elevational view of the cover hinge and auxiliary support.

The main ironing table 10 is preferably formed of a thickness of sheet metal which may, if desired, have its end portions 11 folded downwardly about each of the upright members 13 and 14. The uprights 13 and 14 are also preferably formed of sheet metal construction and in the preferred embodiment of the invention here illustrated are of sufficient dimensions that the upright member 13 may house the ironing machine motor, gear box and other driving mechanism (not shown) by which the inner roll 15 is driven.

As will be seen from examination of Fig. 3, the ironer roll 15 is rotatably mounted on any suitable roll bracket 16 and is adapted to cooperate with an electrically heated ironing shoe 17, the operation of which is also mechanically controlled in a manner well understood in the art. For this purpose a knee control lever 18 is mounted in the upright 14 and a treadle 19 extends between the uprights 13 and 14 in a position convenient for foot operation. The mechanical details of the ironer mechanism do not, however, form any part of the present invention and will, therefore, not be described in greater detail.

The preferred form of machine cover comprises a sheet metal front panel 21 and a similar sheet metal rear panel 22, which are preferably pressed into the desired shape and united by spot welding their upper end portions to the pair of connecting strips 23 and 24. Each of the panels 21 and 22 and each of the end strips 23 and 24 includes an arcuately curved upper edge portion 25, over which a top panel 26 is fitted. The panel 26 may thus be secured to the front and rear panels 21 and 22 and to the connecting strips 23 and 24 in any desirable manner, as, for example, by spot welding, so that the entire machine cover

acts as a unitary construction and forms a three-sided roll enclosure, resembling an inverted U in shape. Longitudinally extending ribs 27 may be formed in the connecting strips 23 and 24 in order to add rigidity to the structure without the necessity of utilizing heavier gauge metal.

The roll enclosure is mounted on the ironing table 10 by means of a pair of bracket hinges 31, which are secured to the ironing table 10 in spaced relationship along its rear edge. Each of these bracket hinges 31 comprises a stationary member 32, which is welded to the table 10 and which includes a pair of flanges 33 through which rivets 34 are mounted to provide a pivotal support for the flanges 35 of an upper or movable hinge member 36. This upper hinge member 36 is secured to the rear panel 22 by welding in order that the entire three-sided roll enclosure may be swung upwardly from its closed position, illustrated in Figs. 1 and 2, to its open position illustrated in Fig. 3.

The movement of the roll enclosure about the hinge is limited by brace 37 mounted on the rivet 38 extending between the flanges 35 on the upper hinge member 36. This brace 37 extends downwardly through the orifice 39 punched in an outwardly extending lower end portion 41 of the bracket 32 and through an orifice 42 formed in the rear wall 43 of each of the uprights 13 and 14. A cross pin 45 is set in the brace 37 to act as a limiting stop for the hinge. It will be seen that while the cross pin 45 is of such length that it may be accommodated between the flanges 33 of the bracket 32, it is too long to pass through the orifice 39 and thus when it is brought into abutment with the portion 41 of the bracket 32, the members 32, 36 and 37 will form a right angle triangle and rigidly support the machine enclosure in the position shown in Fig. 3.

The work table extensions 51 and 52, each comprises a work contacting surface 53, which is preferably of sheet metal and each is mounted in an outer panel 54, which is curved inwardly about its marginal edges and which includes a marginal flange 55 welded to the work contacting surface 53. Each of these table extensions is mounted on the table 10 by means of a pair of hinges 56 and 57. To form these hinges 56 and 57, recesses 61 are punched in spaced-apart position along the edges of the table 10 and each of these recesses extends through an inner reinforcing thickness of metal 62 forming a part of one of the uprights 13 or 14. A pair of flanges 63 are struck inwardly from the down-turned end portion 11 of the table 10 and are spaced apart a suitable distance so that a stamped hinge member 64 of substantially U-shaped cross section may be mounted between them on the hinge pin 65. The outwardly extending end of the hinge 64 projects through an orifice 66 in the plate 54 and passes under a sheet metal strap 67 spot welded to the plate 54. To facilitate manufacture and assembly, these parts are so fitted together that the hinge 64 may slide longitudinally between the strap 67 and the plate 54 in such a manner that the main portion of the machine, comprising the table 10 and the supporting members 13 and 14, may be assembled and painted as a unit and that the table extensions 51 and 52 may thereafter be assembled by telescoping the hinges 64 into the proper orifices 66. An angle member 68 is secured to the plate 53 by means of a clip 69 and is pierced at 71 to provide a spring portion 72 under which the plate extension 73 of the hinge 64 may be forced

at the time of assembly. The tension exerted by the spring portion 72 is sufficient to clamp the flat end portion 73 of the hinge 64 against the outer plate 54 of the table extension 51 and prevent any possibility of accidental disengagement of these parts. Limited stops are provided at the inner end of the hinge 64 by allowing the side flanges 74 to extend inwardly a sufficient distance so that they may contact the limiting rail 75 secured to the under surface of the table 10 and thus establish the extreme downward limit of movement of the table extensions 51 and 52.

A coiled wire toggle spring 76 is so formed that its end portions 77 and 78 assume positions along the lines parallel with the axis of the coil. The end portion 77 is passed through punched openings 79 in each of the upturned flanges of the hinge 64 and the end portion 78 is similarly mounted in punched openings 81 in each of a pair of spaced apart bracket members 82. This construction provides a cross center toggle spring mechanism effective to urge the table extension 51 downwardly when the parts are in their operating position, as shown in full lines in Fig. 4, but when the table extension 51 is manually raised to its vertical or closed position, as indicated by dotted lines in Fig. 4, the end portion 77 of the spring 76 will cross the center established between the hinge pin 65 and the spring portion 78 and will then operate to urge the table extension 51 to the left, as viewed in the drawings, and hold it snugly against the open end of the three-sided ironer cover, as indicated by the dotted line position shown in Fig. 4.

The entire machine body is mounted on casters 81 to permit the operator to move the machine easily when not in use.

Means are provided, however, to restrain the cabinet against such movement while the machine is being operated, since it is desirable at this time that the machine remain slidably fixed in position on the floor and not subject to accidental movement. To this end a pair of vertical slide rods 82 are mounted in brackets 83 affixed to the rear surface of each of the uprights 13 and 14 and are provided with rubber feet 84 which will bear against the floor and lock the cabinet against movement. The feet 84 are lifted from the floor when the machine cover is closed, due to the action of the coiled compression springs 85 that are telescoped on the vertical slide rods 82 in such a manner as to rest upon the upper surface of the brackets 83 and bear upwardly against the washers 86 affixed to the extreme upper end of the slide rods 82.

In order to move the feet 84 downwardly into engagement with the floor automatically whenever the machine cover is opened, a link 87 is pivotally mounted on a rivet 88 on the brace 37 of each of the bracket hinges 31, and these links 87 extend downwardly to operate the slide rods 82. The operative connection between the links 87 and the slide rods 82 is completed by a pair of pressure plungers 89 pinned to the lower ends of the links 87 and slidably in the brackets 91, one of which is welded to the rear surface of one of the uprights 13 and 14 directly above each of the slide rods. These brackets 91 extend downwardly a sufficient distance to engage and act as guides for the upper ends of the slide rods 82, and act as housings for the coiled compression springs 92 positioned between the flattened heads 93 of the plungers 89 and the washers 86 affixed to the top of the slide rods 82.

When the machine cover is lifted from the ironer, the bracket hinges 31 pivot from the position shown in Fig. 7 to that shown in Fig. 8. The braces 37 move downwardly, and through the action of the links 87, cause the plungers 89 to press downwardly on the springs 92 and slide rods 82. The springs 92 overcome the relatively light springs 85 and force the slide rods 82 downwardly until the rubber feet 84 contact the floor.

- 5 10 15 20 25
- 10 The arrangement is such that on a level floor the further movement of the bracket hinges 31 to the extreme position established by the limiting stop cross pin 45 will compress the springs 92 and hold the feet 84 firmly against the floor under the pressure of these springs.

The pressure of these feet 84 on the floor provides sufficient friction to prevent the machine from being readily moved, notwithstanding the fact that a considerable portion of its weight is still carried by the casters 81, and this result will be accomplished even though the floor upon which the machine stands is not perfectly smooth, since the compressed springs 92 act as compensators and permit the feet 84 to adjust themselves to any ordinary variations in the contour of the floor.

When the machine cover is opened, as shown in Fig. 3, its weight is not balanced, and while it is true that the base of support provided by 30 the four casters 81 is sufficiently broad to maintain the cabinet in stable equilibrium, the center of gravity of the structure has been changed and it is, therefore, desirable to alter the base of support, as is accomplished by bringing the two feet 35 84 into contact with the floor so that they too may act as points of support.

From the foregoing description it will be apparent that when the machine is in closed position each of the work contacting surfaces, namely, 40 the upper surface of the table 10 and the work contacting surfaces 53 of the table extensions 51 and 52, will be completely enclosed in such a manner as to preclude any accumulation of dirt or dust. The importance of this feature 45 can hardly be over-estimated since when not in use machines of this nature are left uncared for in basements, laundry rooms and other places where they are subject to exposure to unusual quantities of dust and dirt that would otherwise 50 accumulate upon the work contacting surfaces and prevent the machine from being of any service until it had been thoroughly cleaned. In the present construction when the machine is moved into its operative position, each of the surfaces 55 that has been exposed to dust during the idle period of the machine, is moved into such position that the garments being ironed will not contact them and consequently cannot become soiled during the ironing process.

60 65 70 75 80

While I have shown and described the present preferred embodiment of this invention in compliance with the patent statutes, it is subject to numerous changes and modifications without departing from the invention spirit, and I therefore do not wish to be limited except as by the scope of the appended claims.

I claim:

1. An ironing machine cabinet comprising a table upon which an ironer roll and shoe are cooperatively mounted, a three-sided ironer machine cover hingedly mounted on the ironer table and including open end portions adjacent each end of the ironer roll, table end extension panels hingedly secured to the ironer table at each end thereof, means housed within the walls of the

ironer cabinet for limiting the downward movement of said table extension panels about the hinges, means for moving said hinged table end extension panels upwardly about the hinges in such a manner as to form end panels of the said three-sided ironer enclosure and close the open end portions thereof, and spring means within the walls of the ironer cabinet for alternately resiliently urging said table members into either of aforesaid positions.

2. An ironing machine cabinet comprising a table upon which an ironer roll and shoe are co-operatively mounted, a three-sided ironer machine cover hingedly mounted on the ironer table and including open end portions adjacent each end of the ironer roll, table end extension panels hingedly secured to the ironer table at each end thereof, means housed within the walls of the ironer cabinet for limiting the downward movement of said table extension panels about the hinges, and hinge means for moving said hinged table end extension panels upwardly about the hinges in such a manner as to form end panels of the said three-sided ironer enclosure and close the open end portions thereof.

3. In combination with a domestic machine, a machine cabinet, friction reduction mechanisms for said cabinet whereby it may be readily moved on a supporting floor, a machine cover comprising a plurality of panels adapted to move between an inoperative position wherein the several panels cooperate to enclose the machine, and an operating position wherein the machine is exposed, cabinet anchoring means comprising a plurality of friction members capable of being resiliently held in engagement with the floor and effective to anchor the cabinet against movement, means responsive to the movement of the said machine cover for causing said anchoring means to operate, and means responsive to the movement of said machine cover for causing said anchoring means to release.

4. In combination with a domestic machine, a machine cabinet, friction reduction mechanisms for said cabinet whereby it may be readily moved on a supporting floor, a machine cover adapted to move between an inoperative position and an operating position, cabinet anchoring means effective to anchor the cabinet against movement, means responsive to the movement of the said machine cover for causing said anchoring means to operate, and means responsive to the movement of said machine cover for causing said anchoring means to release.

5. In combination with a domestic machine, a machine cabinet, supporting means establishing a base of support of substantially constant area, a machine cover comprising a plurality of panels adapted to move between an inoperative position wherein the several panels cooperate to enclose the machine, and an operating position wherein the machine is exposed, and effective to alter the center of gravity of the structure by this movement; auxiliary supporting means comprising a plurality of movable floor contacting members movable between an operating and an inoperative position, and means responsive to the movement of the machine cover for causing said auxiliary supporting means to operate to alter the effective base of support of the machine.

6. In combination with a domestic machine, a machine cabinet, supporting means establishing a base of support of substantially constant area, a machine cover adapted to move between

an inoperative position and an operating position, and effective to alter the center of gravity of the structure by this movement; auxiliary supporting means spaced apart from the first mentioned supporting means and movable between an operating and an inoperative position, and means for causing said auxiliary supporting means to operate to increase the effective base of support of the machine.

10. 7. In combination with a domestic machine, a machine table, fixed supporting means establishing a base of support of substantially constant area, friction reduction devices on said supporting means whereby the table may be readily moved on a supporting floor, auxiliary supporting means positioned outside of the base of support defined by the fixed supporting means, friction members on said auxiliary supporting means, means to move the auxiliary supporting means to bring said friction members downwardly to anchor the table against movement and to increase the effective base of support, and yieldable spring devices associated with said auxiliary support to permit firm engagement on floor surfaces of irregular contour.

8. In combination with a domestic machine, a machine table, fixed supporting means establishing a base of support of substantially constant area, friction reduction devices on said supporting means whereby the table may be readily moved on a supporting floor, auxiliary supporting means positioned outside of the base of support defined by the fixed supporting means, friction members on said auxiliary supporting means, and means to move the auxiliary supporting means to bring said friction members downwardly to anchor the table against movement and to increase the effective base of support.

40. 9. In combination with a domestic machine, a machine table, fixed supporting means establishing a base of support of substantially constant area, friction reduction devices on said supporting means whereby the table may be readily moved on a supporting floor, auxiliary supporting means, friction members on said auxiliary supporting means, means to move the auxiliary supporting means to bring said friction members downwardly to anchor the table against movement relative to the supporting floor, and yieldable spring devices associated with said auxiliary supports to permit firm engagement on floor surfaces of irregular contour.

55. 10. An ironing machine cabinet comprising a table upon which an ironing roll and shoe are co-operatively mounted, an ironing machine cover mounted on the ironer table consisting of a back panel, a top panel, a front panel and relatively narrow edge strips at each end of said panels whereby said rear, top, and front panels are rigidly united to form a hood including open end portions adjacent each end of the ironer roll, shiftable extension panels secured to each end of the ironer table by hinges, said panels being smaller than the cross-sectional dimensions of the hood and larger than the open end portions, said hinges being constructed and arranged to permit the extension panels to swing between a horizontal position contiguous with the table top and a vertical position wherein the extension panels will lie closely adjacent the edge strips of the rear, top and front panels to close the open ends of the machine cover.

JOHN A. CASTRICONE.
